GAME BOARD

Sander W. Kuchlin, 10 Pauchogue Ave., East Islip,
Long Island, N.Y.

Filed Feb. 5, 1964, Ser. No. 78,537

Term of patent 14 years

(Cl. D34—5)

The sole figure is a perspective view of a game board showing my new design.

The broken line showing of a marble is for illustrative purposes only. The side of the game board not shown is substantially similar to the side shown and the rear of the game board is plain.

I claim:

The ornamental design for a game board, substantially as shown and described.
